UNITED STATES PATENT OFFICE.

THOMAS E. BARNUM, OF MILWAUKEE, WISCONSIN, ASSIGNOR TO THE CUTLER-HAMMER MFG. CO., OF MILWAUKEE, WISCONSIN, A CORPORATION OF WISCONSIN.

LOCKOUT SWITCH.

Continuation of application Serial No. 800,700, filed November 13, 1913. This application filed February 5, 1915, Serial No. 6,247. Renewed December 22, 1920. Serial No. 432,600.

To all whom it may concern:

Be it known that I, THOMAS E. BARNUM, a citizen of the United States, residing at Milwaukee, in the county of Milwaukee and State of Wisconsin, have invented new and useful Improvements in Lockout Switches, of which the following is a full, clear, concise, and exact description, reference being had to the accompanying drawing, forming a part of this specification.

This invention relates to an electromagnetically operated switch.

It will be explained as applied to a switch in which two separate and independent electromagnets, one a holding magnet and the other an actuating magnet, act in opposition upon a pivoted beam or other means which control the movable switch contact.

Such a switch is disclosed in United States Letters Patent No. 1,151,550, August 24, 1915, issued to George H. Whittingham.

It is particularly adapted to control resistance which is employed to start an electric motor, but it may be applied to other purposes.

The beam is biased to an initial position to open the switch and movable to a final position to close the switch.

The two electromagnets have the windings thereof connected in series with each other and the motor armature so that both windings are subjected to the same variation in current as the motor armature.

The separate and independent magnets exert relatively varying pulls in opposition to each other under similar variations in current so that the holding magnet predominates when the current is abnormal or above a predetermined value and the actuating magnet predominates when the current is normal or at or below such predetermined value.

As a result, if the current rises above the predetermined value at which the beam is to be actuated to close the switch, as occurs when the motor armature circuit is first closed or resistance is removed therefrom, the holding magnet retains the beam in its initial position and keeps the switch open until the motor armature speed in-

creases sufficiently to cause the current to subside to such predetermined value, and then the actuating magnet overcomes the holding magnet and operates the beam to move it to its final position and close the switch.

Among the objects of this invention are:

To provide the actuating magnet with means which will cause its pull to lag further behind a suddenly rising current than the holding magnet pull, and

To cause the holding magnet to exert a high pull to seal the switch contacts when the beam is moved to its final position to close the switch.

To produce a lockout switch which is efficient and which may be readily and economically manufactured.

In accordance with this invention, the actuating magnet has a comparatively closed magnetic circuit of relatively low reluctance so that sufficient eddy currents will be created to produce a high counter magneto-motive force, under a sudden increase in current, to oppose the rise in flux.

The magnetic circuit may further be provided with a shunt or by-pass in parallel to the armature. This shunt or by-pass initially diverts flux from the armature and increases the flux in the magnet pole pieces, thereby causing a further delay in the pull upon the armature due to the flux diverted therefrom and the increased eddy currents.

When the armature is attracted and approaches the magnet pole pieces, the flux, which previously passed through the shunt, traverses the armature and thus a materially increased pull is created thereon.

This application is a continuation of application Serial No. 800,700, filed November 13, 1913.

An embodiment of the invention is illustrated in the accompanying drawings, in which the views are as follows:

Fig. 1 is a side elevation of the switch.

Fig. 2 is a vertical section, the switch being open.

Fig. 3 is a vertical section, the switch being closed.

Fig. 4 shows two pull curves when the switch is closed, one being of the closing

magnet with the shunt and the other being of a similar magnet without the shunt.

Fig. 5 is a diagram comparing the pull characteristics of the actuating or closing magnet and the holding or lockout magnet.

Fig. 6 is a diagram showing the flux in the magnetic circuit of the closing magnet with the shunt and the flux in the magnetic circuit of a similar magnet without the shunt.

Fig. 7 is a diagrammatic view of a controller employing the lockout switch set forth herein.

The switch has a beam 1 and two separate and independent electromagnets, an actuating or closing magnet 2 and a holding or lockout magnet 3.

The beam 1 is mounted upon a pivot 4, and carries a pivoted movable contact 5, which may engage a fixed contact 6. It is biased to an initial position, wherein the switch is open, contacts 5 and 6 being separated, and is movable to a final position wherein the switch is closed. A stop 7 fixes the initial position in which the beam normally stands.

The actuating and holding magnets act upon the beam on opposite sides of its pivot. The pull of the actuating magnet tends to move the beam to close the switch and the pull of the holding magnet tends to retain the beam in its initial position and keep the switch open.

The actuating magnet has two pole pieces, an inner pole piece 8 and an outer pole piece 9, connected together at one end and separated at the other. The outer end of pole piece 9 is provided with a shunt 10, which, with a short air gap 11, forms a magnetic shunt or by-pass to the armature.

The actuating magnet has a comparatively closed magnetic circuit of relatively low reluctance. The shunt provides a by-pass in parallel to the armature so that, in initial position of the beam, a relatively large proportion of the flux in the actuating magnet is diverted from its armature and exerts no pull thereon. As the beam approaches its final position the proportion of the flux diverted from the armature decreases.

The holding magnet has a single pole piece 12, and an adjustable armature 13 carried by the beam. In initial position the air gap between the pole piece 12 and armature 13 is less than the air gap between the pole pieces of the actuating magnet and its armature.

The holding magnet has a comparatively open magnetic circuit of relatively high reluctance.

The actuating and holding magnets have separate and independent magnetic circuits so that the magnetic fluxes, and the pulls exerted thereby upon the beam, are independent of each other.

When the beam is in initial position and the switch is open the greater portion of the flux created by current passing through the winding of the actuating magnet passes through outer pole piece 9 and shunt 10 across air gap 11 back to the inner pole piece. A smaller portion of the flux passes through outer pole piece 9, beam 1, and across the longer air gap between the inner pole piece and the armature, back to the inner pole piece. The flux, passing through shunt 10 and across air gap 11, exerts no pull upon the beam, although this flux acts to magnetize the pole pieces. A smaller percentage of the flux, passing across the air gap between the armature and inner pole piece, exerts a pull upon the beam tending to move it from its initial position and close the switch.

The actuating magnet, having a comparatively closed magnetic circuit, will increase the flux therein for increases in current at low values comparatively greater than will the holding magnet which has a comparatively open magnetic circuit. On the other hand, at comparatively high current values the flux created in the actuating magnet will not increase as greatly for increases in current as will the flux in the holding magnet. The pull of the magnets, which depends upon the flux therein, consequently varies by different ratios when the current changes occur at higher and lower values.

Fig. 5 shows curves representing the pull characteristics of the actuating and holding magnets for a given range of current values. Curve C shows how the pull of the actuating magnet varies with the current and curve H illustrates how the pull of the holding magnet varies over the same current range. At the lower current values the pull of the actuating magnet increases to a greater extent, for a given current increase, than does the pull of the holding magnet. For relatively higher current values the reverse condition obtains.

In practice the current rises suddenly when the armature circuit is closed or resistance is removed therefrom. As the speed of the motor and consequently the counter electromotive force rises comparatively slowly, the armature current subsides slowly to normal. The switch, in order to protect the motor against excessive current, remains open, to keep resistance in circuit, when the current rises suddenly above the critical value but closes to exclude resistance when the current slowly subsides to the critical value.

When the motor current rises suddenly eddy currents are induced in the magnetic circuits of the actuating and holding magnets. These eddy currents produce counter magneto-motive forces which oppose and retard the rise of the flux in the magnet.

The comparatively large conducting mass of the outer pole piece causes the production of comparatively heavy eddy currents in the actuating magnet so that the rise of its flux and consequently the increase in its pull on the beam lags behind the rise of the flux and pull of the holding magnet. Thus the pull of the actuating magnet does not predominate to close the switch as the current 10 suddenly rises above the critical value.

As the speed of the motor increases, the current slowly subsides to the critical value. The comparatively slow change in the current creates comparatively small eddy currents and there is consequently little opposition to the decrease in the flux in either 15 magnet. The pull characteristic of the actuating magnet is thus changed but slightly if at all and at the critical current the pull 20 of the actuating magnet predominates and moves the beam from its initial position to its final position to close the switch.

The outer pole piece, in addition to assisting in the magnetization and the alteration 25 of the pull characteristic of the actuating magnet cooperates with the armature thereof to augment the pull produced by the actuating magnet as the beam approaches the magnet and after it reaches 30 its final position.

When the beam is in its initial position a comparatively large proportion of the flux through the inner pole piece is shunted or by-passed from the armature, and accordingly produces no pull upon the beam. When the beam approaches its final position and the pulling air gap decreases in 35 length, a smaller amount of the flux passes through the shunt or by-pass including the outer pole piece and air gap 11 and more of the flux passes into beam 1 and across the pulling air gap. Thus the pull of the actuating magnet increases materially as the beam approaches its final position. 40 When the beam reaches its final position, the pulling air gap is completely or almost completely closed and practically all of the flux passes into the armature and is effective to maintain the beam in final position 45 with the switch closed.

The effect of the by-pass upon the pull and flux of the actuating magnet is graphically shown by the curves of Figs. 4 and 6.

In Fig. 4 the pull in pound-inches is plotted as ordinates and the current in the winding as abscissæ. Curve D represents the sealing pull of an actuating magnet having a by-pass and curve E represents the sealing pull of an actuating magnet without the by-pass. The curves show that the sealing pull is greater for each value of the current when a by-pass is employed and that the pull becomes relatively greater as 50 the current value is increased.

In Fig. 6 the flux in the core of the actuating magnet with and without a by-pass is plotted as ordinates and the current in the winding is plotted as abscissæ. The flux, for every current value, is higher when 70 the by-pass or comparatively closed magnetic circuit is used than when no by-pass or a comparatively open magnetic circuit is used. The curves show how the magnetization of a closed circuit magnet increases 75 more rapidly than the magnetization of an open circuit magnet.

Fig. 7 diagrammatically illustrates the application of the switch set forth herein to control the starting resistance for an electric motor.

The motor has an armature 14 and a shunt field 15 which are connected to positive line 16 and negative line 17.

The armature current is regulated by 85 starting resistances 18, 19 and 20.

These resistances are controlled by switches 21, 22 and 23, respectively.

In order to start the motor, the switch 24 is closed by closing the switch 25.

Current then flows from the conductor 90 16 through switch 24, magnets 2 and 3 of switch 21, resistances 18, 19 and 20, armature 14, to negative line 17.

As the armature is at rest, the current 95 may become abnormal, and then the switch 21 is held open by its holding magnet 3.

When the armature accelerates sufficiently to make the current subside to a critical value, the switch 21 is closed by its 100 actuating magnet 2.

The resistance 18 is then short-circuited and the switch 22 has the windings of its magnets connected in circuit.

If the current becomes abnormal, due to 105 the resistance 18 being removed from circuit, the switch 22 will be held open by its holding magnet until the motor armature accelerates sufficiently to reduce the current to a critical value.

When the switch 22 closes, it short-circuits the resistance 19, and the switch 23 has the windings of its magnets connected in circuit.

When the switch 23 finally closes, it removes resistance 20 from circuit.

Of course, various modifications may be made in the switch set forth herein and the application thereof without in any way departing from the invention.

Having shown and described an embodiment of my invention, what I claim as new and desire to secure by Letters Patent, is,

1. An electromagnetic appliance having a pivoted member normally biased to one position and movable to another position, a pair of electromagnets acting on said member in opposite directions, said electromagnets having independent magnetic circuits and different pull characteristics when sub- 130

jected to the same change in current so that one predominates under current above a predetermined value and the other predominates under current below a predetermined value, and means for causing the pull of the second electromagnet to increase less rapidly than the pull of the first electromagnet under sudden rises of current.

2. An electromagnetic switch having a pivoted member normally biased in one position, two electromagnets acting in opposite directions upon said member and having independent magnetic circuits and different pull characteristics when subjected to similar current conditions so that one electromagnet predominates to hold said member in its initial position under current above a predetermined value and the other electromagnet predominates to move said member to another position under current below a predetermined value, and means to delay the increase in pull of the second electromagnet under a sudden rise of current.

3. An electromagnetic switch having a pivoted member normally biased in one position and movable to another position, two magnetically independent electromagnets subject to the same current conditions and acting on said member in opposite directions one to assist in holding said member in its initial position and the other for moving said member, said electromagnets having different pull characteristics whereby the one assisting in holding said member in its initial position predominates under current above a predetermined value while the other predominates under current below a predetermined value, and means for delaying the predominance of the second electromagnet when subjected to suddenly increasing current.

4. An electromagnetic switch having a movable member pivoted intermediate its ends, a pair of electromagnets acting on said member in opposite directions, said electromagnets having independent magnetic circuits and different pull characteristics when subjected to similar current variations so that one predominates under current of abnormal value and the other predominates under current below an abnormal value, and means for delaying the increase in pull of the second electromagnet when the current changes suddenly.

5. An electromagnetic switch having a pivoted member movable to two positions, a pair of electromagnets exerting opposing pulls upon said member, said electromagnets having independent magnetic circuits and different pull characteristics so that when subjected to the same current conditions the pull of one electromagnet predominates under current above a predetermined value and the pull of the other predominates under current below a predetermined value, and

means for retarding the increase in pull of the second electromagnet under sudden rises of current below the predetermined value.

6. An electromagnetic switch having a member pivoted intermediate its ends and normally biased in one position, a holding electromagnet for assisting in retaining said member in its initial position, an actuating electromagnet acting in opposition to said holding electromagnet to move said member to another position, said electromagnets being subjected to the same current conditions but having independent magnetic circuits and exerting relatively varying pulls on said member under different current values so that the holding electromagnet predominates under current above a predetermined value and the actuating electromagnet predominates under current below a predetermined value, and means for retarding the preponderance of the actuating electromagnet under sudden rises of current below the predetermined value.

7. An electromagnetic switch having a pivoted member, two electromagnets acting upon said member to attract it in opposite directions, said electromagnets having independent magnetic circuits and different pull characteristics so that one predominates under current above a predetermined value and the other predominates under current below a predetermined value, and means for causing a part of the flux of one electromagnet to be diverted from attracting said member until after said member approaches said electromagnet.

8. An electromagnetic switch having a pivoted member initially biased in one position and movable to another position, two electromagnets acting in opposite directions upon said member and having independent magnetic circuits and different pull characteristics when subjected to similar current conditions so that one predominates under current above a predetermined value and the other predominates under current below a predetermined value, and means for decreasing the flux of the second electromagnet acting upon said member in its initial position.

9. An electromagnetic switch having a pivoted member, two electromagnets acting upon said member to attract it in opposite directions, said electromagnets having independent magnetic circuits and different pull characteristics so that one predominates under current above a predetermined value and the other predominates under current below a predetermined value, and means for diverting a part of the flux of the second electromagnet from attracting said member before said member is moved, such part of the flux diminishing as said member approaches said electromagnet.

10. An electromagnetic appliance com-

prising two separate and independent electromagnets one having a comparatively closed or low reluctance magnetic circuit and the other having a comparatively open or high reluctance magnetic circuit, and a movable member attracted in opposite directions by said electromagnets.

11. An electromagnetic appliance comprising two separate and independent electromagnets one having a comparatively closed or low reluctance magnetic circuit and the other having a comparatively open or high reluctance magnetic circuit, and a movable member attracted in opposite directions by said electromagnets, the low reluctance magnet having a magnetic shunt including an air gap between its poles and in shunt with its armature.

12. An electromagnetic appliance having a movable member movable from one position to another, a relatively low reluctance or closed magnetic circuit magnet to move said member to one position, and a separate relatively high reluctance open magnetic circuit magnet to hold said member in the other position.

13. An electromagnetic appliance having a movable member movable from one position to another, a relatively low reluctance or closed magnetic circuit magnet to move said member to one position, and a separate relatively high reluctance open magnetic circuit magnet to hold said member in the other position, such magnets having different changes in pull under the same changes in current.

14. An electromagnetic appliance having a member movable between two different positions, a relatively low reluctance or closed magnetic circuit magnet to attract said member in one direction, and a separate relatively high or open magnetic circuit magnet to attract said member in the opposite direction, the magnetic circuit being smaller and the ampere turns greater upon the first magnet than upon the second.

15. An electromagnetic appliance com-

prising two separate and independent electromagnets one having a comparatively closed or low reluctance magnetic circuit of 50 relatively large cross-section and the other having a comparatively open or high reluctance magnetic circuit, and a movable member attracted in opposite directions by said electromagnets, the low reluctance magnet 55 having a magnetic shunt including an air gap between its poles and in shunt with its armature to provide a supplemental flux to increase the magnetization and decrease the initial pull upon the armature. 60

16. An electromagnetic appliance having a movable member, and two separate and independent electromagnets acting in opposite directions upon said member, one having a relatively open or high reluctance 65 magnetic circuit and the other having a relatively closed or low reluctance magnetic circuit, the second magnet having a magnetic shunt with an air gap between its poles and in shunt with its armature to 70 provide an additional flux to augment the normal increase in pull upon the armature as it approaches such magnet.

17. An electromagnetic appliance comprising a movable member provided with an 75 armature, a low reluctance or closed magnetic circuit magnet to attract said armature, said magnet having a magnetic shunt with an air gap between its poles and in shunt with its armature so as to provide an 80 additional flux to attract the armature and augment the normal increase in pull thereon as it approaches the magnet, and an electromagnet acting under an abnormal current to hold said member from being moved by 85 the aforesaid electromagnet.

In witness whereof, I have hereunto subscribed my name in the presence of two witnesses.

THOMAS E. BARNUM.
